Primary Examiner — Khawaja Anwar*(74) Attorney, Agent, or Firm* — Hayes Soloway P.C.(57) CLAIM

The ornamental design for an eye guard for a medical mask, as shown and described.

DESCRIPTION

The broken lines form no part of the claimed design and are for illustrative purposes only.
